UNITED STATES PATENT OFFICE.

LEOPOLD HAUSLEHNER, OF VIENNA, AUSTRIA-HUNGARY, ASSIGNOR TO ISIDOR LANDAUER AND FERDINAND BLOCK, OF VIENNA, AUSTRIA-HUNGARY.

PACKING FOR STUFFING-BOXES.

SPECIFICATION forming part of Letters Patent No. 718,345, dated January 13, 1903.

Application filed April 11, 1901. Serial No. 55,433. (No model.)

To all whom it may concern:

Be it known that I, LEOPOLD HAUSLEHNER, a subject of the Emperor of Austria-Hungary, residing at Vienna, in the Province of Lower Austria, in the Empire of Austria-Hungary, have invented certain new and useful Improvements in Packings for Stuffing-Boxes; and I do hereby declare the following to be a full, clear, and exact description of the invention, such as will enable others skilled in the art to which it appertains to make and use the same.

This invention relates to packing more especially designed for the packing of stuffing-boxes; and it consists, essentially, of thin strips obtained from a galvanic deposit of a metal softer than iron, preferably copper, assembled into a bundle or bunched and twisted into a rope or bunched and plaited.

20 In carrying out my invention I form an electrodeposit of a suitable ductile metal, preferably copper, upon any suitable material so prepared that the deposited film of metal can be removed and cut up into narrow strips, which may then be bunched, or a bunch of such may be twisted into rope form, or the bunches may be plaited.

In order to obviate the labor of removing the film of deposited metal before cutting it up into strips, I may deposit the metal upon a suitable thin flexible fibrous material—as, for instance, paper or a textile fabric—in which case a film of metal is deposited upon one side of the material, and the latter is then cut up into strips. Of course such a film may be deposited upon both sides or surfaces of the material, if it is desired, though this I do not deem absolutely necessary.

Electrodeposition of metals as well as the 40 electrodeposition of such upon fibrous materials, as paper or textile fabrics, is well known and will therefore not need a detailed description. I may state, however, that the best results are obtained with comparatively thin

films of metal or when the latter is deposited 45 upon a backing of the character of thin paper or of a light textile fabric.

Referring now to the accompanying drawings, Figure 1 shows a packing *a*, of electrodeposited metal, in longitudinal section. 50 Figs. 1^a and 1^b are cross-sections of packing-strips cut from sheets of paper or a textile fabric having one or both surfaces metallized. In Fig. 1^a, *m* indicates the metallic deposit, and *p* the paper or textile fabric of the strip 55 *a'*, and in Fig. 1^b, *p* indicates the strip of paper or textile fabric of the packing-strip *a'*, and *m* the metallic deposit on opposite faces of said strip. Fig. 2 shows a number of strips *a* or *a'* or *a''* bunched together. Fig. 3 shows 60 such bunch twisted into rope form; and Fig. 4 shows bunches of the strips *a*, *a'*, or *a''* plaited.

Practice has shown that packing made as above described is much superior to the 65 fibrous or metallic packings hitherto used in that it wears better and is not as liable to result in leakage.

I have hereinabove stated that the strips are narrow and of course very thin, so that 70 all the figures of drawings are drawn to an exaggerated scale.

Having thus described my invention, what I claim as new therein, and desire to secure by Letters Patent, is—

1. A packing consisting of bunched flexible strips of an electrodeposited and suitable metal, for the purpose set forth.
2. A packing consisting of twisted or plaited bunches of strips of an electrodeposited and 80 suitable metal, for the purpose set forth.

In testimony that I claim the foregoing as my invention I have signed my name in presence of two subscribing witnesses.

LEOPOLD HAUSLEHNER.

Witnesses:

JOSEF RÜBRESCH,
ALVESTO S. HOQUE.

It is hereby certified that the name of the last-mentioned assignee in Letters Patent No. 718,345, granted January 13, 1903, upon the application of Leopold Hauslehner, of Vienna, Austria-Hungary, for an improvement in "Packing for Stuffing-Boxes," was erroneously written and printed "Ferdinand Block," whereas said name should have been written and printed *Ferdinand Bloch*; and that the said Letters Patent should be read with this correction therein that the same may conform to the record of the case in the Patent Office.

Signed and sealed this 3d day of March, A. D., 1903.

[SEAL.]

F. I. ALLEN,
Commissioner of Patents.
